UNITED STATES PATENT OFFICE.

GEORGE C. STRROUP, OF JERSEY CITY, NEW JERSEY, ASSIGNOR OF ONE-HALF TO
JOHN H. BRADSHAW, OF PALISADES, NEW JERSEY.

CAR-COUPING RELEASE.

1,380,122.

Specification of Letters Patent.

Patented May 31, 1921.

Application filed September 16, 1919. Serial No. 324,196.

To all whom it may concern:

Be it known that I, GEORGE C. STRROUP, a citizen of the United States, and resident of Jersey City, county of Hudson, and State of New Jersey, have invented certain new and useful Improvements in Car-Coupling Releases, of which the following is a specification and which are illustrated in the accompanying drawings, forming a part thereof.

10 This invention relates to means for withdrawing coupling pins and has for an object the provision of a device of this nature that shall not be injured by the movements of the draft gear due to buff, draft, or 15 rounding of curves in the track.

An illustrative embodiment of the invention is shown in the accompanying drawings in which—

Figure 1 is an elevation of a device embodying the invention shown as applied to the end of a car;

Fig. 2 is a plan view of this device removed from the car, on a larger scale;

Fig. 3 is an elevation of the device seen from the right of Fig. 1 with a portion of the car in section;

Fig. 4 is a section on line 4—4 of Fig. 3 looking upward and

Fig. 5 is a detail section on line 5—5 of 30 Fig. 3.

The end sill of a car is indicated at 10, the buffing plate at 11 and a coupler of well known type at 12.

For operation of the device embodying 35 the invention there is shown a lever as 13 pivoted upon a stub shaft, as 14, which may be formed integral with a base plate, as 15, shown as secured to a portion of the car end, as the buffing plate 11. Lever 13 is shown 40 as adapted to be operated for withdrawal of the coupling pin, as 17, by a pull upon a rod, as 18, preferably having the handle end supported in a bracket, as 19, adjacent the side of the car.

45 Stub shaft 14 may be formed with a reduced portion, as 20, providing a shoulder against which the lever 13 may seat, and the lever may be retained by a washer, as 21, and cotter pin, as 22.

50 To apply the lifting force to the coupling pin 17, a hook, as 23, may be connected with the pin, as by a link 24. In order to allow the hook to move longitudinally in response to lateral motion of the coupler when the

car rounds curves in the track the shank, as 55 25, of the hook is shown as loosely passed through and freely slidable in a pair of loops 26, 26, which loops may be cast integral with an arm, as 28, projecting laterally from lever 13 above the pivot 14 thereof. 60 If the shank 25 of the hook is formed round, as shown, it will be rotatable in the loops.

To allow the hook 23 to follow longitudinal movement of the coupler due to draft 65 or buff, the arm 28 is preferably pivotally supported on lever 13. This may be readily accomplished if the end of lever 13 be provided 70 with a cylindrical depression or socket, as 29, and if the arm be provided 75 with a pin, as 30, to fit the depression. Preferably a portion of the wall of the socket 29 is made thicker at the top, as at 31, than elsewhere so as to provide a dovetailed form of wall, and the arm 28 is provided 80 with an arcuate slot, as 32, which is dovetailed in vertical cross section, as plainly shown in Fig. 5, to mate with the socket wall. A portion of the socket wall is made of equal thickness from top to bottom, as at 85 33, and therefore if the arm 28 be revolved about the pin 30 through an angle of 180° from the position shown in the drawing, it may be freely removed.

The arms 13 and 28 with the hook 23 and 85 its shank 25 constitute a bell crank having an extensible arm, the arm made up of parts 25 and 28 pivotally mounted on the other arm. While, strictly speaking, the portion 90 13 below the pivot 14 constitutes one arm of the bell-crank, and the arm 28, shank 25 and socket 33 constitute the other arm, yet it is preferred to regard the socket 33 as a portion of the first arm of the bell-crank for the following reasons: The action of the 95 bell-crank to lift the coupler pin would be fully accomplished if the horizontal or weight arm of the crank extended directly from the pivot. The sole function of the extension of arm 13 upward beyond the 100 pivot to provide socket 33, is for the purpose of pivoting the weight arm of the bell-crank on the power arm. An equivalent construction would be a socket corresponding to 33, laterally offset from arm 13 and located at 105 the left of stub-shaft 20, as seen in Fig. 3. The expression "one arm pivotally mounted on the other arm" is to be read as applying to

the structure illustrated and its equivalents. The arm 28 and the hook 23 and its shank 25 also constitute means having universal movement in a single plane adapted to move with 5 a coupling pin and when so considered the arm 13 constitutes means to move the first named means out of its plane of movement to pull the pin. By reason of this universal movement the device may be operated to 10 pull the pin irrespective of any lateral or longitudinal change of position of the coupler, and no injury to the release device will result from such changes of position.

Many changes may be made in the physical embodiment of the invention without departing from its spirit.

I claim as my invention—

1. In a coupling release, in combination, a bell crank pivoted adjacent the coupling, 20 said bell crank comprising two arms, one arm being extensible, the extensible arm as a whole pivotally mounted on the other arm, means for connecting the extensible arm to the coupling pin, and means for moving the 25 bell crank about its pivot.
2. In a coupling release, in combination, a lever adapted to be pivotally mounted adjacent the coupler, an arm pivoted as an entirety to said lever on an axis perpendicu- 30 lar and adjacent to the pivot of the lever, means to connect said pivotally mounted

arm to a coupling pin, and means connected to said lever for distant operation thereof.

3. In a coupling release, in combination, a 35 lever adapted to be pivoted adjacent to a coupler and having a long and a short arm, said short arm having a cylindrical socket the wall of said socket being thickened through a portion of its circumference adjacent the opening of the socket, an arm having 40 a projecting pin adapted to enter said socket, and an arcuate slot widened at its bottom to mate with said thickened wall, and means to connect said arm to a coupling 45 pin.

4. A coupling release comprising a bell- 50 crank lever adapted to be pivoted to a car, one arm as a whole being laterally oscillatable about the other arm and being extensible, said oscillatable and extensible arm being adapted to be connected to a coupling pin.

5. A coupling release comprising a bell- 55 crank lever adapted to be pivoted to a car, one arm being laterally oscillatable about the other arm, the oscillatable arm comprising two portions one of which is longitudinally movable on the other, the longitudinally movable portion thereof being rotatable.

GEORGE C. STROUP.
